TRAFFIC MARKING FOR ROAD SURFACES

Francis Nicholson, Chard, England

Application June 12, 1942, Serial No. 446,751
In Great Britain July 3, 1941

1 Claim. (Cl. 94—1.5)

This invention relates to traffic markings for road and similar surfaces and has for its object to provide means by which traffic lanes and direction symbols can be marked in a permanent manner on pavements or roadways without having to recess the surface of the road and without interrupting the use of the roadway during the process of application.

According to this invention a traffic marking comprises a moulded slab of wear-resistant and preferably resilient moulded material, such as rubber, artificial rubber or other plastic or resinous compound having an insertion or backing of woven material of larger area than the slab, which is moulded in one with the slab to form a reinforcement therefor and to provide a free margin of woven material extending around the slab and adapted to be cemented to the road by means of a material appropriate to the surface of the road.

Preferably the slab is formed of a strip of rubber or other relatively resilient composition which is capable of retaining its colour and resisting wear, and the reinforcing backing or insertion may be formed of wire, hessian, cotton or other woven fabric which is interposed during the moulding of the slab and is subsequently vulcanised therewith.

At least two parallel sides of the slab are bevelled and in some cases both the sides and ends of the slab are bevelled. These bevelled portions preferably slant downwardly towards a narrow margin of the material from which the main part of the slab is formed but in all cases a free surround or outer margin of woven material extends preferably around the slab.

When the slab is to be applied to the road, the surface of the latter is painted with any ordinary road tar or bitumen so that the area so coated is slightly greater than that of the fabric surround. The slab is then placed in position on the surface so coated and the fabric surround is usually given a second coating by means of a brush, this coated area being then covered with asphalt, chippings or grit as in the wellknown methods of surface dressings before being finally tamped or rolled. The asphalt or stone chippings are applied so that the fabric is entirely covered and preferably the edge of the rubber or like slab is made to merge into the road surface by sloping off the asphalt or similar surface dressing.

In some cases the main body of the slab may be of sufficient thickness to receive, for example at each end, reflex glasses inserted in recesses of

sufficient depth to protect the glass from damage by vehicles having rigid tires. Further, where the slab is to be used in a wood block or similar roadway the reinforcement may be of woven wire and provided with eyeleted holes to receive screws or spikes to form an additional means of securing the strip to the road surface.

Various embodiments according to the present invention are illustrated by way of example in the accompanying drawing, in which

Figure 1 is a plan showing a moulded rubber or like road slab with a free surround of woven material,

Figure 2 is a cross-section on the line II—II of Figure 1 but showing the slab after application to the road,

Figure 3 shows a modified form of slab in which the reinforcement is composed of wire fabric with additional perforations therein,

Figure 4 is a longitudinal section through a modified form of slab having reflex glasses therein at each end, and

Figure 5 is an end view of Figure 4 partly in section.

In the simplest form of slab shown in Figures 1 and 2 the main body of the slab A is composed of rubber, artificial rubber or other resilient moulded composition which is wear-resisting, waterproof and adapted to retain its colour permanently. The slab is reinforced with a backing of relatively loosely woven material, such as hessian, linen or cotton, or relatively fine metallic wire mesh. The area of the fabric B is greater than that of the slab so that a free surround or margin extends around the slab whilst the remaining parts of the fabric are integral with the slab and form a reinforcement therefor. The fabric is moulded with the main portion of the slab and in the case of rubber or similar material

is subsequently vulcanised therewith. The slab is provided with bevelled ends and sides and between the edges of the free surround and the edges of the main body there is an intermediate margin A¹ of rubber or of the material from which the main body is formed, forming a thin step of this material as clearly shown in Figure 2. This inner margin or step provides a sure seal against the inroad of water and relieves flexing strains between the fabric and the main body

thus reducing any tendency for the fabric to separate or fracture where it joins the main body.

The alternative construction shown in Figure 3 differs from that above described in that the reinforcement D is formed of woven wire or the

like or wire mesh provided with perforations D¹ to form a key for the cement or adhesive employed and to serve as openings for screws or spikes if the slab is to be applied to a road having a surface of wood blocks or material suitable to receive spikes. If desired the wire fabric surround may be cut or reduced so that projecting lugs only are provided around the slab which, as before, is composed of rubber or similar material E. No intermediate margin is shown in the particular construction illustrated in Figure 3 but such a margin may be provided if desired.

In the alternative construction shown in Figures 4 and 5 the slab is of increased depth and comprises a main body of rubber or the like F provided with a wire or woven fabric reinforcement G which is of greater area than the slab and with an intermediate resilient margin F¹ as in the construction shown in Figure 1. The body of the slab F is recessed so as to form a housing at each end for one or more reflex glasses H which are retained in position by means of a plastic cement or like packing J against a central core of wood or other relatively rigid material K. It will be seen that as the glasses project beyond the end of the slab they are exposed to rain and hence do not become obscured by mud as is the case with those which are set in a hood or recess. The bevelled edges and ends, where such are provided, prevent the slab itself from holding mud or becoming obscured in use. When the slab contains reflex glasses it is preferably of half-round cross-section as shown in Figure 5.

When the slab is to be applied to the road, an

area of the latter slightly greater than that of the slab with its surround is coated as by means of a brush with hot tar or bitumen. The slab is then laid on the road surface, pressed or tamped into position and the exposed portion of the fabric is preferably given a second coating of tar or bitumen. This coated surface is then covered with asphalt, stone chippings or grit L (Figures 2 and 4) and this coating is preferably sloped off so as to merge into the road surface and cover the intermediate margin A¹ or F¹. Alternatively, where spikes are employed, these are introduced before the asphalt or like dressing is applied.

15 What I claim as my invention and desire to secure by Letters Patent is:

A traffic marker comprising a premoulded slab of wear-resisting material and a backing of untreated woven material having a larger area than the slab moulded in one with the latter whereby a free portion of untreated woven material extends beyond the slab, at least two parallel sides of the slab being bevelled and an outer margin of moulded material integral with the main portion of the slab surrounding the bevelled sides, said margin lying between the bevelled portion of the slab and the free portion of woven material and formed of the same material as the main body but of lesser thickness than said main body, the 20 whole constituting a single completed article the underside of which is adapted to be cemented to the normal road surface.

FRANCIS NICHOLSON.
